UNITED STATES PATENT OFFICE.

RODNEY S. OWEN, OF SOUTH STUKELY, QUEBEC, CANADA.

VENTILATOR AND HEATER.

SPECIFICATION forming part of Letters Patent No. 352,097, dated November 2, 1886.

Application filed February 2, 1886. Serial No. 190,619. (No model.)

To all whom it may concern:

Be it known that I, RODNEY S. OWEN, a citizen of the United States, at present residing in South Stukely, county of Shefford, Province of Quebec, Canada, have invented a new and useful Improvement in Ventilators and Heaters, of which the following is a specification, reference being had to the annexed drawings, forming a part thereof, in which—

10 Figure 1 is a vertical transverse section of my improved ventilator and heater. Fig. 2 is a detail view of the cold-air-damper regulator. Similar letters of reference indicate corresponding parts in both figures of the drawings. 15 The object of my invention is to provide an attachment to stoves for receiving air from the exterior of the building and heating it before its distribution in the building; and to this end the invention consists in the peculiar construction and arrangement of parts, as hereinafter fully described, and pointed out in the claims.

20 The drum A, which forms the body of the heater, is closed by heads a b, the head a having an inwardly-projecting collar, c, for receiving the stove-pipe d, the head b having an outwardly-projecting collar, c', for receiving the stove-pipe d'. Air-flues e extend lengthwise through the drum A, and around the collar c' of the lower head of the drum is formed an annular chamber, f, which communicates with all the flues e, and is provided with a cold-air pipe, B, which leads to the exterior of the building in which the heater is placed.

25 In the center of the drum A is supported a short length of pipe, C, axially in line with the pipe d d', but not communicating directly with the pipe. The pipe C is supported from the heads of the drum by rods g. In the pipe C is placed a damper, h, whose spindle i extends through the sides of the drum A, and one end of the spindle is provided with an eye, j, forming the handle of the damper.

30 A pipe, k, extending through the bottom of the annular chamber f and upward into one of the tubes E, is closed at the top, and has attached to the bottom thereof a diaphragm-case, D, formed of two oppositely-arranged cups, l, clamped together upon the flexible diaphragm m. To the center of the diaphragm m is secured a rod, n, which passes through the lower cup, l, and is connected with an arm, o, secured

to the spindle p of a damper, q, placed in the cold-air pipe B.

The drum A may be located in any desired position in the stove-pipe d d', and the cold-air pipe B may enter at the bottom of the chamber f, or at the side, as may be required. When the damper h is opened, the products of combustion pass from the pipe d' directly through the pipe C to the pipe d; but when the damper h is turned so as to close the pipe C the products of combustion are compelled to pass outside of the pipe C in contact with the flues e. The pipe k contains air, and when the heater is cold the air contracts and the diaphragm m is drawn upward, as shown in Fig. 2, closing the damper q in the cold-air pipe B; but when the flues are heated and the air in the pipe k is expanded the diaphragm m is pushed downward by the expansive force of the air, and acting upon the arm o of the damper q, through the rod n, turns the damper into a position parallel with the air-pipe, allowing air to enter the chamber f, whence it passes through the flues e into the room, the air being heated in its passage.

35 By causing the variations of temperature in the drum A to operate the damper in the cold-air pipe I am enabled to regulate the admission of cold air to the room, so that when the drum is cold the cold-air pipe will be automatically shut, thus preventing the wind from blowing into the room through the pipe and through the heater; but when the drum A is heated, the damper in the cold-air pipe being always open, air may readily enter.

40 The air introduced to the room through the heater, being warmer than the air contained by the room, rises and displaces the air in the upper portion of the room, while the foul air in the lower part of the room escapes through the stove with which the heater is connected, or through the various crevices and openings around the windows and doors.

45 I am aware that a heating-drum adapted to be connected to a stove-pipe at opposite ends, and having air-flues therein and means for deflecting the products of combustion against said flues, is old, and I am also aware that an automatic diaphragm-damper for regulating the admission of cold air is likewise old, and I therefore do not claim such inventions.

50 Having thus described my invention, what I

claim as new, and desire to secure by Letters Patent, is—

1. The heating-drum A, having the inwardly-projecting collar c at its upper end and the outwardly-projecting collar c' at its lower end, and provided with the annular chamber f around the collar c', the air-flues e, extending lengthwise through the drum and communicating with the annular chamber, and the cold-air pipe communicating with the annular chamber f, substantially as herein shown and described.

2. The combination, with a drum provided with air-flues and a cold-air pipe, of a valve in the cold-air pipe, a pipe extending into one of the air-flues and having its upper end closed, a diaphragm in the lower end of the said pipe, and a connection between the diaphragm and the valve, substantially as herein shown and described.

RODNEY S. OWEN.
